DESIGN FOR A HINGE

James H. Boye, Chicago, Ill., assignor to James H. Boye Manufacturing Company, Chicago, Ill., a corporation of Illinois

Application June 11, 1947, Serial No. 139,593

Term of patent 14 years

(Cl. D10—9)

To all whom it may concern:

Be it known that I, James H. Boye, a citizen of the United States, residing at Chicago, in the county of Cook and State of Illinois, have invented a new, original, and ornamental Design for Hinge, of which the following is a specification, reference being had to the accompanying drawing, forming part thereof.

In the drawing:

Figure 1 is a top plan view of a hinge embodying my new design;

Figure 2 is a side elevational view of the hinge; and

Figure 3 is a bottom plan view of the hinge.

I claim:

The ornamental design for a hinge, as shown.

JAMES H. BOYE.
